A. A. HARTZELL

STOPCOCK

Filed Sept. 13, 1923

FIG. 1.

FIG. 2.

INVENTOR
Arthur A. Hartzell
BY
Edward R. Lomax
ATTORNEY

UNITED STATES PATENT OFFICE.

ARTHUR A. HARTZELL, OF SHIPPENSVILLE, PENNSYLVANIA.

STOPCOCK.

Application filed September 13, 1923. Serial No. 662,436.

To all whom it may concern:

Be it known that I, ARTHUR A. HARTZELL, a citizen of the United States, residing at Shippensburg, in the county of Clarion and 5 State of Pennsylvania, have invented certain new and useful Improvements in Stop-cocks, of which the following is a specification.

The objects, construction and operation of 10 my improved stopcock are herein set forth with sufficient clearness to enable others skilled in the respective arts to which its construction and use respectively relate, to make and use the same.

15 In certain classes of service, as in oil pipelines in the oil-fields and in refineries, much difficulty is experienced with the matter of leakage of stopcocks. If the plug is sufficiently loose in the body to turn as easily as 20 it should it is liable to leak, especially under the high pressure to which it is commonly subjected in both oil lines and lines conveying natural gas from the wells, also when hot oil is being passed through it. Because 25 of this, it is a common practice, after a stopcock has been closed, to drive the plug firmly to its seat in the body by means of a hammer or any other convenient tool and then tighten up the nut which secures the plug 30 of the commonly-employed stopcock within the body. Thereafter when the stop is to be opened, it is necessary to loosen said nut and by means of a hammer to free the plug from its firmly-seated position before it can be 35 turned to open the stop. This is a source of much annoyance, inconvenience, delay and often considerable danger, in all classes of service, but especially so in gas lines in which a pressure of as high as eight hundred 40 pounds is common; if the operator is not careful in manipulating and loosening the plug, it may be blown from the body, causing loss of life and property. There is danger, though not so great, in other classes of 45 service, such as steam, hot oil, and compressed air, though hot oil is the most troublesome of all common substances to handle, as it is most likely of all to leak from the stop-cock.

50 It is, therefore, the object of this invention to provide a simple and efficient stopcock which overcomes or is free from the objections above set forth, and one in which the plug may be easily, quickly and safely loosened and tightened as required.

The construction whereby I am enabled to secure said objects is clearly shown in the accompanying drawings in which:

Fig. 1 shows my improved stopcock partly in side elevation and partly in section taken 60 longitudinally and centrally of the body.

Fig. 2 is an elevation of the adjacent side of Fig. 1.

The construction shown in said drawings is substantially as follows:

The body 1, in general construction is much the same as that usually employed in stopcocks but differs therefrom in the respect that at the larger end thereof the periphery of said body is provided with a 70 screw-thread 2 for a purpose to be presently set forth. Said body is supplied with the usual pipe-bosses 3 having the usual tapped ports 4 for the attachment of piping; said body also has a tapered plug-chamber 5 for 75 the reception of the tapered, rotative plug 6.

Said plug is provided upon the larger end with an axially-aligned screw-threaded member 7 adapted to the purpose of actuating said plug longitudinally so as to loosen and tighten the same within its chamber; said plug is provided upon the other end with a square head or tang 8 for the purpose of actuating same rotatively as in opening and closing the stopcock.

A cap 9 is provided for the screw-threaded end of said body and is connected thereto by means of said screw-thread 2, said cap being provided with a downwardly-projecting annular flange 10 which is internally screw-threaded for cooperation with said thread 2. Said cap is also provided with a centrally-positioned opening which is internally threaded for the reception of and cooperation with said plug-member 7 and the screw-thread thereon.

The thread 2 of said body, and the thread 7' of said plug-member 7 have differing leads, and preferably opposite leads, in which case the thread 2 is a left-hand thread 100 and the thread 7' is a right-hand thread.

The cap 9 is provided with a suitable head 11 for the application of a wrench to turn the same.

The plug 6 is provided with the usual fluid-passage 12 for alinement and registry with the ports 4 of the body 1 as when the stopcock is opened, and to be turned into non-registry with said ports, as when the stop is closed.

The operation of this stop-cock is as follows:

When the plug 6 is to be turned to open the stopcock, a wrench is applied to the head 11 and the cap 9 is turned in the direction indicated by the arrow in Fig. 2; this actuates said plug longitudinally within its chamber and loosens it therein; said plug is then turned to the open position whereupon said cap is turned in the direction opposite to that indicated by the arrow thus actuating the periphery of said plug into leak-tight contact with the chamber walls of the body. When the stopcock is to be closed, said cap is again turned in the direction indicated by the arrow to loosen the plug, the plug is then turned to its closed position, whereupon it is again actuated to its leak-tight position by turning said cap in the direction reversely to that indicated by the arrow.

In some classes of service, where only a moderate pressure has to be contended with, it may not be necessary to actuate the cap, as the turning of the plug alone will, to a certain extent, actuate the same longitudinally, thus seating and unseating the same, as above set forth.

As previously stated, the pressure which must, in some kinds of service, be withstood by stops of this class in which my invention is embodied, is as high as eight hundred pounds per square inch, hence the construction must be, and my construction is, so devised that the stress due to such pressure, exerted upon the weakest point, namely, the plug member 7, is a compressive stress, instead of a tensile stress in order to

prevent rupture at said weakest point, and also to prevent the plug from being blown from the body, should such rupture occur.

I claim the following:

A stop cock comprising in combination, a body having a tapered plug-chamber extending through the same, laterally-extending fluid ports leading into said chamber, a cap secured to said body at the larger end of said chamber by means of co-operating screw-threads supplied to said cap and said body, said cap having also a screw-threaded opening of opposite lead to said first-mentioned threads and arranged in concentric alinement with said chamber, said cap being further supplied with a wrench-head adapted for turning said cap, and a tapered plug revolvably carried in said chamber having fluid passages extending transversely therethrough arranged to be turned into and out of alinement and registry with said body-ports, said plug having at the larger end thereof an axially-aligned screw-threaded member adapted for co-operation with said screw-threaded opening in said cap in such manner that said plug may be actuated to and from leak-tight contact with the adjacent walls of said body by the turning of said cap, said plug being also supplied with a tang adapted to turn the same to open and close the valve.

In testimony whereof I affix my signature 70 in presence of two witnesses.

ARTHUR A. HARTZELL.

Witnesses:

FRED A. RAY,
JOHN L. McBRIDE.
